UNITED STATES PATENT OFFICE.

GEORGE THOMPSON, OF GRAND RAPIDS, MICHIGAN.

CAR-DOOR.

Specification of Letters Patent. Patented Sept. 20, 1921.

Application filed July 16, 1919. Serial No. 311,356.

To all whom it may concern:

Be it known that I, GEORGE THOMPSON, a citizen of the United States of America, residing at Grand Rapids, in the county of Kent and State of Michigan, have invented 5 certain new and useful Improvements in Car-Doors; and I do hereby declare the following to be a full, clear, and exact description of the invention, such as will enable 10 others skilled in the art to which it appertains to make and use the same.

This invention relates to doors, particularly doors used on freight cars. This door of my invention is adapted for use on freight 15 cars which carry grain or other loose produce and it is an object and purpose of the invention to produce a door, very simple in construction and operation and containing many improvements in both manufacture 20 and use over that shown in my previous patent issued November 9, 1915, No. 1,159,550 and adapted for the same purpose. The present invention comprises many novel constructions and arrangements of parts for 25 greatly simplifying the door and making it more practical as will appear fully and in detail in the following description, taken in connection with the accompanying drawing, in which—

30 Figure 1 is a rear elevation of the door.

Fig. 2 is a horizontal section taken through the door and adjacent portions of the car on which it is mounted, and

35 Fig. 3 is a vertical section through the door and adjacent portions of the car.

Like reference characters refer to like parts in the different figures of the drawing.

The door is adapted to be slidably mounted on the car so as to cover a side opening therewith, as usual, the vertical posts at each side of the door opening being indicated at 1. On the inner side of each post 1 a channel member is attached comprising a web 2 which lies against the inner side of the post 40 and front and rear inwardly extending flanges 3 and 4, the latter of which is of greater width than the former. The channels extend from the lower portion of the door opening upwardly for a distance but 45 not the full height of the opening. Upper and lower rods 5 connect the flanges 3 and 4 of each channel, said rods inclining downwardly at an angle from rear to front, and also inclining outwardly from rear to front 50 as shown in Figs. 3 and 2. The usual car 55

door 6 is mounted to slide back and forth over the opening, the usual fixtures 7 for mounting the door being used, as well as a track for the upper rollers to run on, this being old and well known. The track is at 60 attached directly over the upper edge of the opening and to the part 9 of the car above said opening.

In the upper portion of the door an opening 10 is made adapted to be closed by a 65 door 11. Through this opening a chute may be passed for the entrance of grain into the car after the door is closed. Likewise in the lower portion of the door a second opening 12 is made, adapted to be covered by a 70 suitable closure 13 which may be moved to one side for the grain to pass out of the car when the door is closed as will later appear.

A plate 14 of heavy sheet metal, practically of the same height as the channels 75 and of a width slightly wider than the distance between the inner edges of the flanges 4 of the channels is located behind the door and connected thereto. A number of horizontal rods 15 are located one above the other 80 on the rear side of the door and rotatably mounted thereon in bearings 16. From each of said rods arms 17 extend rearwardly connecting to other horizontal rods 18 located in front of the plate 14 and rotatably mounted in bearings 19 fixed to the front side of the plate. A bar 20 is mounted on the rods 5 in each of the channels normally sliding down the rods 5 against the flanges 3 and 85 lying, when in such front position, so that its inner edge does not extend beyond the edge of the flange. The flanges 3 have portions cut away at 3^a as shown for the passage of the extended ends of the rods 18, which engage against the bars 20 and force the same 90 to the rear when the plate 14 moves from its upper position against the rear side of the door to lower position against the front sides of the flanges 4. This movement of bars 20 to the rear brings them inward as they traverse the inwardly inclined rods 5 from front to rear and against the front of the plate 14 at its vertical side edges as shown in Fig. 2, locking the plate 14 against movement except when it is elevated and turned forward 100 against the back of the door.

To lift the plate 14, a chain 21 is attached to the plate and passed through an opening in the door 6 and fastened to a lever 22 at a point between the ends thereof, the upper 110

end of the lever, as shown in Fig. 3, being pivotally attached to the door below the opening for passing the chain through the door. Normally the weight of the plate 14 5 will cause it to go to lower position and the lever is turned upwardly and into the dotted line position shown in Fig. 3. By grasping the lever and pulling down on the same the plate may be elevated and turned so as to 10 lie against the rear side of the door whereupon it may be moved on the track 8 to one side to open the car. When the plate 14 is in lower position its lower edge bears against the sill 24 at the lower side of the door opening 15 making a tight connection or engagement therewith.

The plate 14 has an opening 25 in its lower portion directly behind the opening 12 in the door which may be normally closed by 20 a slide 26 mounted on the front side of the plate. Said slide is movable to uncover the opening and may be moved from in front of the opening when the door is shut by first moving the cover 13 of opening 12 to one 25 side and then reaching in and operating the slide 26.

When the car is to be filled with grain, the door is closed and the plate 14 placed in lower position to which it naturally drops 30 by gravity and the grain entered into the car through the opening at 10. The grain fills the car and presses against the rear side of the plate 14, the pressure being a direct horizontal pressure which is resisted by the arms 35 17 and by the locking bars 20 which, when a direct forward horizontal pressure is brought against their rear sides tend to bite against rods 5 and be thus held against movement, this locking the plate 14 from movement under the pressure against it. When the car reaches its destination, the openings 12 and 25 are uncovered permitting the escape of grain until enough has been taken from the car directly back of the plate 14 to permit 40 the plate to be lifted, whereupon the plate is lifted and the door moved to one side.

The operation of the door with the attachments thereon is simple and the construction is of few parts and readily manufactured 50 and installed at comparatively low cost. It saves boarding up the door opening back of the door for the grain to bear against and the loss of the lumber needed for such operation. This lumber can seldom be used over 55 again as it is shattered and rendered unfit for reuse when it is knocked loose after the car reaches its destination. This construction is more economical and simple in construction than that of my former patent and it serves to hold the grain back from the door quite as well.

I claim:

1. In combination with a car having a side opening therein, vertical posts at the sides 60 of said opening, channel members attached

on the inner sides of said posts and including front and rear flanges, said front flanges being narrower than the rear flanges, rods disposed between the flanges of each channel and disposed downwardly and forwardly 70 at an angle to the horizontal from rear to front and also outwardly and away from the door opening at an angle to the webs of the flanges from rear to front, vertical bars slidably mounted on the rods, one in each channel member, a door slidably mounted on the car and adapted to cover said side opening in the car, a plate located back of the door of a width to pass between the front flanges 80 of the channels but wider than the distance between the rear flanges thereof, horizontal rods pivotally mounted one above the other on the front side of the plate, the ends of said rods extending beyond the edges of the plate, arms projecting forward from each 85 rod and connected to other rods mounted horizontally on the rear side of the door, whereby the plate may be elevated and moved forward against the rear side of the door or lowered to bear against the front 90 sides of the rear flanges of the channel members, said front flanges having openings therein to pass the ends of the rods attached to the plate so that said rods serve to move the vertical bars backward against the vertical side edges of the plate, and means for elevating the plate from the outside of the door.

2. In combination with a car having a side opening therein, vertical posts at the sides 100 of the opening, channels attached on the inner sides of the posts having inwardly extending front and rear flanges, the front flanges being of less width than the rear flanges, spaced apart rods connecting the 105 flanges of each channel member, said rods extending upwardly and inwardly at angles to the horizontal and the webs of the channels from front to rear, vertical bars, one in each channel member slidably mounted on 110 the rods, a door mounted on the car to close the side opening therein or move away therefrom to uncover it, a vertical plate disposed behind the door of a width to pass between the front flanges of the channel but greater 115 than the distance between the rear flanges thereof, means for connecting the plate to the door whereby said plate may be elevated and moved forward closely against the rear side of the door or lowered and moved backward to rest against the rear flanges of the channels and on the floor of the car, means for raising the plate, and means operable for engaging against the bars and moving them backward against the plate as the plate 120 is lowered and moved backward, substantially as described.

3. In combination, a car having a side opening therein, a door slidably mounted on the car and adapted to open or close said 130

opening therein, a plate disposed vertically at the rear of the door, connections for attaching the plate to the door whereby the plate may be elevated and moved forward 5 against the rear side of the door or lowered and moved back from the door into said opening in the side of the car when the door is in closed position, means for elevating and moving the plate forward from 10 within the doorway, means located at the sides of the opening against which the vertical side portions of the plate bear when in lower position, and means movably mounted in front of said first means for locking 15 the plate against movement from a direct horizontal pressure applied to the back of the plate, said means being movable forward and laterally and disengaging from the plate as the plate is elevated and moved 20 forward, and means for engaging the same and moving it rearwardly and against the

plate as the plate is lowered and moved to the rear, substantially as described.

4. In combination, a car having a side opening therein, a door slidably mounted 25 thereon for opening or closing the door opening, a vertically positioned plate attached to the rear side of the door and connected thereto so that it may be elevated against the rear side of the door or lowered 30 and moved backward a distance into the opening in the car, means for moving the plate against the rear side of the door from without the door, and means automatically operable as the plate is lowered and moved 35 backward for engaging the same and locking it against forward movement from direct horizontal pressure applied to its rear side, substantially as described.

In testimony whereof I affix my signature.

GEORGE THOMPSON.
